Des. 212,025

Patented Aug. 20, 1968

212,025

CULTIVATING TOOL

Ephraim Pede, 4332 Regent St.,
Duluth, Minn. 55804

Filed Jan. 22, 1968, Ser. No. 10,246

Term of patent 14 years

(Cl. D39—1)

FIG. 1 is a side elevational view of a cultivating tool embodying the new design.

FIG. 2 is a front elevational view thereof.

FIG. 3 is a rear elevational view thereof.

FIG. 4 is a top plan view thereof.

FIG. 5 is a bottom plan view thereof.

I claim:

The ornamental design for a cultivating tool, as shown.
